UNITED STATES PATENT OFFICE.

FRANK J. GIBBONS, OF WORCESTER, MASSACHUSETTS.

SAFETY DEVICE FOR PRESSES.

Application filed July 10, 1922. Serial No. 573,915.

To all whom it may concern:

Be it known that I, FRANK J. GIBBONS, a citizen of the United States, residing at Worcester, in the county of Worcester and State of Massachusetts, have invented a new and useful Safety Device for Presses, of which the following is a specification.

This invention relates to a device for preventing the descent of the plunger of a hand fed press from catching and injuring the hand of the operator.

The principal object of the invention is to provide a positive acting means which can absolutely be depended upon to act every time the plunger descends, even if that descent is irregular or accidental, to positively withdraw the hand of the operator from a position under the plunger which it normally assumes when feeding blanks to the press. The invention also involves the provision of means to be worn on the wrist of the operator to co-operate with the other mechanism to positively insure the above mentioned action and the provision of this mechanism in a simple and inexpensive form suitable for attachment to any ordinary type of press.

Further objects and advantages of the invention will appear hereinafter.

Reference is to be had to the accompanying drawings, in which—

Fig. 1 is a side view of a press of well known type with a preferred embodiment of this invention applied thereto, and shown in position for feeding the blanks to the press when the plunger is raised;

Fig. 2 is a front elevation showing the parts in the position assumed when the plunger is depressed;

Fig. 3 is a side view of certain parts of the device on an enlarged scale;

Fig. 4 is a plan of the attachment worn by the operator with the strap broken away, and

Fig. 5 is a side elevation of the same with the strap and bar which operates the device in section.

The invention is shown as applied to a well known type of reciprocating press to which the operator feeds blanks by hand. This press has the usual table 10 and plunger 11. The rest of the press need not be described as the invention is independent of it. On the plunger is mounted a stud 12 shown in this instance as perforated but preferably having means for the free pas-

sage of a flexible non-stretchable connection 13 which operates the safety device from the plunger. This stud 12 is mounted on the plunger itself and of course it moves up and down with it positively.

The flexible connection 13, which may be in the form of a belt or chain or cable, passes from the stud 12 in opposite direction upwardly and each strand extends over a pulley 14. These pulleys are mounted to swing on links 15 which support them from above. These links are connected at any desired point along a pair of brackets 16 mounted on the frame of the machine above the plunger. The brackets are perforated to receive the links at different distances from the frame of the machine to accommodate different types of presses and work. Each end of the flexible connection 13 passes down from the pulley 14 and is connected with a metal link 17 which is pivoted through one of a series of perforations in an arm 18 fixed to a transverse shaft 19. This shaft is mounted in bearings on a pair of brackets 20 fixed on the press below the table. It also has another arm 21 which is adjustably mounted upon it and is provided with a head 22. These parts are duplicated at the other side of the press. This head has three or more perforations 23 for an operating rod 24. This operating rod extends across the press in front of the table thereof and can be placed in any one of the perforations 23 to locate it at different distances from the table.

From what has been said, it will be obvious that every time the plunger 11 descends both of the strands of the flexible connection 13 will be pulled down at the center and consequently the links 17 will be pulled up. This action is positive and there is no lost motion in it. It results in swinging the head 22 from the full line position in Fig. 1 to the dotted line position.

I am aware of the fact that rods movable toward and from the press table have been suggested before and that the hand of the operator has been rested upon them with the idea that movement of this rod will warn the operator to take her hand out of the way. I make this arrangement positive by providing a strap or bracelet 25 to go around the operator's wrist. This extends under and is secured to a plate 26 which, on account of tightening up the strap, will rest against the lower side of the wrist. Extending

down from this plate is a stop 27 in a plane at right angles to the plate and to the direction of the rod 24. This is preferably hooked over at the bottom so that after 5 having placed it in position, it will engage the rod and the operator will feel the pressure if she lifts her hand away from the rod 24.

In ordinary operation, she has to rest her 10 hand, or rather the plate 26, on the rod with the plate 27 in front of it so that every time this rod moves forward the operator's hand is moved forward by power at the same time and it is moved out of the way before the 15 plunger descends into contact with the table.

This constitutes a positive and certain safety device which, as long as the operator has it on and is working on the press, will never fail to draw the hand away from danger at all times. It does not interfere with the feed of the press by the operator and is comparatively inexpensive to make, and install. It also has no electric connections.

Another advantage is that the device prevents the thrusting of the hand too far into the press at all times.

Although I have illustrated and described only a single form of the invention, I am aware of the fact that modifications can be 30 made therein by any person skilled in the art, and that it can be applied to other types of presses that that shown, without departing from the scope of the invention as expressed in the claims. Therefore, I do not 35 wish to be limited to all the details of construction herein shown and described, but what I do claim is:—

1. The combination with a press having a table and reciprocating plunger, of a flexible connection connected with the plunger and positively moving therewith, a movable transverse rod mounted to move toward and away from the press table, means connected with the flexible connections for moving said 40 rod as the plunger descends, and means adapted to be worn on the wrist of the operator for engagement with said rod.

2. The combination with a press having a table and reciprocating plunger, of a flexible connection connected with the plunger 45 and positively move therewith, a lever connec-

ted with said flexible connection, and adapted to be swung by it on its pivot, said lever having mounted thereon a transverse rod in position to swing away from the press 55 table as the plunger descends, and means adapted to be worn by the operator for engagement with said rod, whereby the hand of the operator will be moved away from the plunger positively every time it descends.

3. In a safety device, the combination with a reciprocating press head and plunger, of a flexible connection movable with the plunger, a shaft transversely located, an arm on 65 said shaft connected with said flexible connection and adapted to be raised by it when the plunger descends, a pair of arms on said shaft having means for supporting a transverse rod, whereby said rod will be moved 70 when the plunger moves, a strap adapted to be worn around the wrist of the operator, and a plate extending down from the strap and adapted to engage the rod to provide for positively moving the operator's hand 75 back when the plunger descends.

4. In a safety device, the combination with a reciprocating press head and plunger, of a flexible connection, means on the plunger for moving said flexible connection as the 80 plunger moves, a shaft, an arm on said shaft connected with said flexible connection and adapted to be raised by it when the plunger descends, a pair of arms on said shaft extending upwardly therefrom and having means for supporting a transverse rod in any 85 one of a plurality of positions, whereby said rod will be moved forward when the plunger descends, a strap adapted to be worn around the wrist of the operator, and a hooked plate 90 extending down from the strap and adapted to engage the rod to provide for positively moving the operator's hand back when the plunger descends.

5. As an article of manufacture, an attachment for a press safety device, a wrist strap having a plate provided with a transversely projecting hook for the purpose described.

In testimony whereof I have hereunto affixed my signature.

FRANK J. GIBBONS.
